US00D868899S

(12) United States Design Patent (10) Patent No.: US D868,899 S
Chen (45) Date of Patent:  Dec. 3, 2019

(54) BUBBLE FAN

(71) Applicant: Bo Chen, Shantou (CN)

(72) Inventor: Bo Chen, Shantou (CN)

(73) Assignee: Shantou P&C Plastic Products Company Limited, Guangdong (CN)

() Term: 15 Years

(21) Appl. No.: 29/594,146

(22) Filed: Feb. 16, 2017

(51) LOC (12) Cl. 21-01

(52) U.S. Cl.

USPC D21/401

(58) Field of Classification Search

USPC D23/370, 377, 385, 411-414; D21/401

CPC A63H 33/28

See application file for complete search history.
